UNITED STATES PATENT OFFICE.

PETER A. SCHAEFER, OF CINCINNATI, OHIO, ASSIGNOR TO THE UNITED STATES PLAYING CARD COMPANY, OF SAME PLACE.

DESIGN FOR A GAME-CHIP.

SPECIFICATION forming part of Design No. 33,715, dated December 11, 1900.

Application filed May 24, 1900. Serial No. 17,892. Term of patent 14 years.

To all whom it may concern:

Be it known that I, PETER A. SCHAEFER, a citizen of the United States, residing at Cincinnati, Hamilton county, State of Ohio, have 5 invented and produced a new and original Design for Game-Chips, of which the following is a specification.

The leading feature of my design is a chip to be employed in the play of poker or other 10 games; and the design consists in a game-chip having the configuration and representation shown in face and edge view in Figures 1 and 2, respectively, in the accompanying drawings.

In the drawings, *a* is a poker-chip bearing 15 thereon the representation of a pair of crossed tenpins 1, with tenpin-balls 2 in the angles formed by the crossed pins, and by a circular figure, (indicated at 4.)

What I claim is—

The design for a game-chip, of substantially 20 the configuration and representation herein shown and described.

PETER A. SCHAEFER.
